CATCH OR SIMILAR ARTICLE

Charles S. Gehrie, Montclair, N.J., assignor to Presto
Lock Co., Garfield, N.J., a limited partnership

Filed Sept. 23, 1963, Ser. No. 76,692

Term of patent 14 years

(Cl. D50—7)

FIG. 1

FIG. 2

FIG. 3

FIG. 4

FIG. 1 is a top plan view of a catch or similar article embodying my new design;

FIG. 2 is an elevational view taken from the bottom of FIG. 1;

FIG. 3 is an elevational view taken from the top of FIG. 1; and

FIG. 4 is an elevational view taken from the right of FIG. 1.

The essential features of my design reside in the full line showing thereof.

I claim:

The ornamental design for a catch or similar article, as shown and described.
